CLAIM

The ornamental design for a finger mounted toothbrush, as shown and described.

DESCRIPTION

FIG. 1 is a front, right and top perspective view of a finger mounted toothbrush showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof, shown in an environment of use;

FIG. 10 is an enlarged view of “10” shown in FIG. 1;

FIG. 11 is an enlarged view of “11” shown in FIG. 1; and, FIG. 12 is an enlarged view of “12” shown in FIG. 7.

The broken lines shown in the drawings depict portions of the article, and form no part of the claimed design. The dot-dash lines shown in FIGS. 1, 7, and 10-12 are for purpose of depicting enlarged view indicators, and form no part of the claimed design. The dot-dash lines shown in FIG. 9 depicting a hand illustrate environmental subject matter, and form no part of the claimed design.

1 Claim, 12 Drawing Sheets
